(57) **CLAIM**

An ornamental design for a “frame for a vehicle,” as shown and described.

DESCRIPTION

FIG. 1 is a front perspective view of a first embodiment of the frame for a vehicle;

FIG. 2 is a rear perspective view of the first embodiment of the frame for a vehicle;

FIG. 3 is a front view of the first embodiment of the frame for a vehicle;

FIG. 4 is a rear view of the first embodiment of the frame for a vehicle;

FIG. 5 is a right side view of the first embodiment of the frame for a vehicle;

FIG. 6 is a left side view of the first embodiment of the frame for a vehicle;

FIG. 7 is a top view of the first embodiment of the frame for a vehicle;

FIG. 8 is a bottom view of the first embodiment of the frame for a vehicle;

FIG. 9 is a front perspective view of a second embodiment of the frame for a vehicle;

FIG. 10 is a rear perspective view of the second embodiment of the frame for a vehicle;

FIG. 11 is a front view of the second embodiment of the frame for a vehicle;

FIG. 12 is a rear view of the second embodiment of the frame for a vehicle;

FIG. 13 is a right side view of the second embodiment of the frame for a vehicle;

FIG. 14 is a left side view of the second embodiment of the frame for a vehicle;

FIG. 15 is a top view of the second embodiment of the frame for a vehicle;

FIG. 16 is a bottom view of the second embodiment of the frame for a vehicle;

FIG. 17 is a front perspective view of a third embodiment of the frame for a vehicle;

FIG. 18 is a rear perspective view of the third embodiment of the frame for a vehicle;

FIG. 19 is a front view of the third embodiment of the frame for a vehicle;

FIG. 20 is a rear view of the third embodiment of the frame for a vehicle;

FIG. 21 is a right side view of the third embodiment of the frame for a vehicle;

FIG. 22 is a left side view of the third embodiment of the frame for a vehicle;

FIG. 23 is a top view of the third embodiment of the frame for a vehicle; and,

FIG. 24 is a bottom view of the third embodiment of the frame for a vehicle.

The broken lines shown in the drawings represent portions of the frame for a vehicle or environment that form no part of the claimed design.
